UNITED STATES PATENT OFFICE.

FRANKLIN L. BARBER AND EDWIN W. WEBB, OF CHICAGO, ILLINOIS, ASSIGNORS TO STANDARD CAR TRUCK COMPANY, OF CHICAGO, ILLINOIS, A CORPORATION OF NEW JERSEY.

CAR TRUCK.

Application filed January 28, 1924. Serial No. 689,019.

This invention relates to a railway truck and particularly to a type of truck known as an arch bar truck.

It is an object of this invention to provide such a truck of simple and efficient construction comprising a side frame having bolster columns in which a vertical movable roller seat is disposed adapted to carry rollers for supporting the end of a bolster arm 5 arranged for endwise movement transversely of the side frame.

It is a further object of the invention to provide a truck comprising a side frame having such bolster columns of U-shape or 15 channel shape in cross section with the open sides facing each other and in the channels of which the roller seat and end of the bolster are disposed for their respective movements.

It is a further object of the invention to provide a truck having such a side frame in which a plurality of springs support a roller seat, said springs being supported at different levels in said side frame and also preferably having their tops disposed at different levels.

It is still another object of the invention to provide a truck having such a side frame and roller seat, which seat has a depressed 30 central portion or channel shape in which the rollers are carried and into which a downwardly projecting central portion of the bolster is disposed, which latter portion rests on the rollers.

It is still another object of the invention to provide such a truck having a side frame with spaced bolster columns and a crown piece connecting the same, which crown piece has a channel extending thereacross, said 40 channel being extended at the outer side of each column and adapted to receive a compression member therein, which compression member is secured by bolts passing therethrough and through the extended portion 45 of said channel.

These and other objects and advantages of the invention will be fully set forth in the following description made in connection with the accompanying drawings in 50 which like reference characters refer to the same parts throughout the different views, and in which—

Fig. 1 is a view in side elevation of a portion of the truck;

Fig. 2 is a horizontal section taken substantially on the line 2—2 of Fig. 1;

Fig. 3 is a view in vertical section of one end of the truck, the bolster being shown in side elevation, this figure being on a reduced scale;

Fig. 4 is a view partly in side elevation and partly in central vertical section of the roller seat; and

Fig. 5 is a view partly in end elevation and partly in central vertical section of the roller seat, the same being shown on an enlarged scale.

Referring to the drawings, a railway truck is shown having a side frame comprising a compression member 1 and a tension member 2, a portion of one wheel of the truck being indicated in dotted lines as 3. The members 1 and 2 converge at the ends of the side frame and extend to the journal box in the usual manner. The side frame also 70 comprises spaced bolster columns 4, which columns are substantially of U-shape or channel shape in cross section, as shown in Fig. 2, and have their open sides facing each other. The columns are joined at the top by a crown piece 5 having a channel extending longitudinally therethrough and the sides and bottom of said channel are extended at the outer sides of the column 4, as shown at 5^a. The compression member 1 75 is secured to the crown piece 5 by headed and nutted bolts 6 extending therethrough and through the bottom of the projected portion 5^a. The columns 4 are joined at their lower ends by a base portion 7, the lower surface 80 of which is formed on a curve, the center of which is disposed in the vertical center line of the side frame. Adjacent the columns the base has projecting flanges 7^a forming channels in which is disposed the lower curved portion of the tension member 2 and it will be noted that the side portions of the members 2 are tangential with their curved portion. The tension member is secured to the 85 base member 7 by headed and nutted bolts 90 passing through the portion 7^a at the sides of member 2, which bolts also extend through clips 8 from which extend the horizontal portions 8^a to which the connecting plank member 9 is riveted. The base member 7 also 95 has a comparatively small pin 7^b projecting into the central hole in the tension member 2. As shown in Fig. 1, the base member 100

7 has a pin 7^c which extends through the side frame and through the tension member 2 to which it is secured. The base member 7 also has a pin 7^d which extends through the side frame and through the compression member 1 to which it is secured.

is formed with a central depressed or channel portion 7^c at the sides of which are raised or shelf portions 7^d. A channel member 10 extends into the portion 7^c of the base member 5 of the side frame and extends transversely thereof to the opposite side frame. A spring plate 11 has side portions seating upon the shelves 7^d and a central depressed or channel portion 11^a resting on the top of 10 the channel 10. This plate 11 forms the bearing for a plurality of springs 12 and said portion 11^a of said plate is of curved formation partially to embrace the outer side of the springs disposed therein. It will thus 15 be seen that the springs 12 are disposed at different levels. In the embodiment of the invention illustrated, there are four of the springs 12 seated in the depressed portion of the plate 11 or the base 7, while there 20 is one spring at each side of these springs which is seated on the raised portion of the plate 11 or of the base 7. Supported upon the top of the springs 12 is a roller bearing member 13. The member 13 also has a central depressed or channel shaped portion 13^a and raised end portions 13^b and has in its central depressed portion the spaced ribs 13^c between which the seats receiving the bearing rollers are formed. The said member 25 13 has depending flanges 13^d at its sides adapted to embrace the springs 12 at their upper ends and has further depending ribs 13^e adapted to be disposed between the end springs 12 and the adjacent springs, as 30 shown in Fig. 2. A central and circular depending flange or rib 13^f is disposed between the four center springs and acts to retain these springs in properly spaced relation. The raised portions 13^b of the member 13, 35 likewise, have depending circular flanges or ribs 13^g adapted to extend into the center of the end springs 12 to hold the same in proper position. The end portions of the 40 roller seat 13 are substantially rectangular 45 in shape and fit loosely into the channels of the columns.

The bolster member 14 has a downwardly projecting central portion 14^a formed with spaced ribs defining the roller seats, which 50 portion extends into the central depressed portion 13^a of the roller seat and is supported upon bearing rollers 15 which rest on the seat 13. The bolster extends over the raised portions 13^b of the seat member 55 and has laterally projecting rectangular portions 14^b disposed in the channel of the columns 4. The width of the portion 14^b is considerably less than the width of the channel in the columns so that endwise play is 60 permitted for the bolster. In one practical embodiment of this invention this lateral play is substantially two inches.

From the above description it is seen that applicants have provided a simple and efficient railway truck in which endwise move-

ment of the bolster is permitted. The bolster and roller seat are compactly housed in the bolster columns and guided therein in their vertical movement and the end of the bolster and the roller seat are compactly arranged. 70 By having the central part of the bolster disposed in the roller seat, additional guiding effect is obtained for the bolster and the sufficient number of supporting springs are provided for, while at the same time, a 75 strong base is retained for the bolster columns. The parts are, therefore very conveniently and compactly arranged and effectively held in proper position in their respective movements. 80

The invention has been used in actual practice and found very efficient for the purpose intended.

It will, of course, be understood, that various changes may be made in the form, details, arrangement and proportions of the parts without departing from the scope of applicants' invention, which, generally stated, consists in a device capable of carrying out the objects above set forth, such as shown and described and defined in the appended claims. 85

What is claimed is:

1. A railway car truck comprising a side frame having spaced bolster columns and a central depressed channel-shaped base portion therebetween with elevated shelf portions at each side thereof, a roller seat having a central depressed channel shaped portion and raised end portions, a plurality of springs supported in the depressed portion of said side frames and supporting the depressed portion of said seat, additional springs supported on the said shelf portions of the side frame and supporting the raised end portions of said seat, said seat having a flange depending from its sides enclosing the upper ends of said springs, and means depending from said seat between said springs for holding the same in 100 position. 105

2. A railway car truck comprising a side frame having spaced bolster columns, a central depressed channel-shaped base portion therebetween with elevated shelf portions at each side thereof, a connecting member of channel shape resting on said depressed portion, a plate having a depressed central portion disposed in said depressed portion of said frame and raised side portions resting on said shelf portions, a plurality of springs supported on the central depressed portions of said plate, additional springs supported on the raised ends of said plate, and a roller seat resting on and supported by all of said springs, the depressed portion of said plate having flanged ends adapted to partially embrace said plurality of springs. 120 125

3. A railway car truck comprising a side

- frame having spaced bolster columns and a crown piece connecting the same having a channel extending longitudinally in its top portion, said crown piece having ends extending at each side of said columns, a compression member seated in said channel, and bolts passing through said compression member in the bottom of said extended portions securing said compression member and columns together.
4. A railway car truck comprising a side frame having spaced bolster columns of channel-shape in cross section with said channels facing each other, a roller seat extending between said columns and vertically movable therebetween, a single set of rollers carried on said seat, a bolster supported on said rollers having lateral projections disposed in said channels of said columns and vertically movable therein, said projections being of less width than the width of said channels whereby longitudinal movement of the bolster transversely of the side frame is permitted, a set of springs beneath the central portion of said roller seat, additional springs at each side of said set of springs, said roller seat having raised extensions at either side of said rollers projecting over and resting on said additional springs and extending into the channels of said columns whereby the weight of said bolster is carried on said rollers and equally distributed by said roller seat over all of said springs.
5. A railway car truck of the arch bar
- type comprising a side frame having spaced bolster columns of channel shape in cross section with said channels facing each other, a roller seat extending between said columns having end portions substantially fitting in said channels and vertically movable therein, a single set of bolster supporting rollers disposed substantially in one plane at the central portion of said roller seat, a central set of springs disposed under the central portion of said roller seat and additional springs at a higher level than said set at each side of said set, said end portions of said roller seat extending over and respectively supported on said additional springs whereby the load on said single set of rollers is distributed over all of said springs.
6. A railway car truck comprising a side frame having spaced bolster columns, a roller seat disposed between said columns, a single set of bolster supporting rollers carried on said roller seat, a set of springs disposed under and supporting the central portion of said roller seat, additional springs at the ends of said set of springs, said roller seat having end portions extending over and supported by said additional springs whereby the load on said single set of rollers is distributed over all of said springs.

In testimony whereof we affix our signatures.

FRANKLIN L. BARBER.
EDWIN W. WEBB.
